REVOLVING COLLAPSIBLE BEAM FOR DYEING-MACHINES.

1,062,493.

Specification of Letters Patent.

Patented May 20, 1913.

Application filed April 4, 1912. Serial No. 688,420.

To all whom it may concern:

Be it known that I, FRANK M. MORTON, a citizen of the United States, residing at Phoenix city, in the county of Lee and State 5 of Alabama, have invented certain new and useful Improvements in Revolving Collapsible Beams for Dyeing-Machines; and I do declare the following to be a full, clear, and exact description of the invention, such as 10 will enable others skilled in the art to which it appertains to make and use the same.

This invention relates to improvements in revolving and collapsible beams for dyeing machines.

15 The objects of the invention are to provide a beam of this character having an improved and simplified means for collapsing the yarn supporting slats thereof and an improved adjustable means for limiting the 20 movement of the slat supporting member when shifted to project or collapse the slats.

Another object is to provide an improved construction of beam heads designed to slidably hold the yarn supporting slats in position 25 and to prevent the channeling of the dye liquor between the ends of the slats and the adjacent portions of the beam heads.

With these and other objects in view, the invention consists of certain novel features 30 of construction, and the combination and arrangement of parts as will be hereinafter more fully described and claimed.

In the accompanying drawings; Figure 1 is a central vertical longitudinal section of 35 my improved beam; Fig. 2 is a vertical cross sectional view thereof on the line 2--2 of Fig. 1; Fig. 3 is a similar view taken on the line 3--3 of Fig. 1; Fig. 4 is a side view of one of the slat expanding members of the 40 beam.

My improved beam comprises a supporting shaft 1 the ends of which are reduced to form shoulders 2, and said ends are threaded a short distance beyond the shoulders 2 as shown at 3 and are extended a considerable distance beyond the threaded portions to form journals 4, by means of which the beam is revolvably supported in the dye tank or tub (not shown). Engaged with 45 one end of the shaft 1 is a head 5, said head being clamped against the shoulder of this end of the shaft by a clamping nut 6, thereby rigidly securing the head to the shaft. On the opposite end of the shaft is arranged

a head 7 which is likewise clamped against 55 the shoulder 2 and rigidly fastened to this end of the shaft by a nut 8, said nuts 6 and 8 being screwed onto the threaded portions 3 of the shaft.

The heads 5 and 7 are provided a suitable 60 distance from their outer edges with annular enlargements 9 and the central portions of said heads are offset on their outer sides as shown. The enlargements 9 are concentric with the center of the heads and have 65 therein an annular series of radial recesses 10 between which are lugs 11 projecting a suitable distance beyond the inner faces of the heads for a purpose hereinafter described. The heads 5 and 7 are connected 70 together and braced by a series of longitudinally disposed tie rods 12, the ends of which project through the heads and are threaded to receive clamping nuts 14 which are screwed into engagement with the outer 75 sides of the heads as shown. The heads are provided on their outer sides with radially disposed bracing ribs 15 and the head 7 has on its outer side a concentric annular flange 16 to receive the tubular beam trunnion. 80 (Not shown).

Slidably mounted on the shaft 1 are a series of slat supporting and expanding rings 17, each of which comprises a central hub 18, a series of radially projecting spokes 19 85 and a rim 20. In the rims 20 are formed series of radially disposed slat receiving notches 21 with which are engaged a series of yarn supporting slats 22. Any number of slat supporting rings 17 may be provided 90 and they are preferably spaced equal distances apart on the shaft 1 and are connected together to move in unison by a pair of connecting rods 23, the ends of which are reduced and threaded to receive clamp- 95 ing nuts 24. The rods 23 extend through suitable apertures in two of the spokes and are arranged diametrically opposite to each other as shown. The reduced ends of the rods are engaged with the end rings 17 100 which are clamped against the shoulders formed by said reduced ends, by the nuts 24. The intermediate rings are spaced apart and held in position on the rods 23 and shaft 1 by cotter pins or similar fastenings 25 105 which are engaged with apertures in the rods on opposite sides of the rings.

The ends of the slats 22 are slidably ar-

ranged in the recesses 10 in the heads 5 and 7 and they work radially between the inwardly projecting elements 11 here shown in the form of lugs or ribs. The radial recesses 10 are of greater length than the depth of the slats, so that the latter may have sufficient radial movement, but the ends of said slats are of such thickness that they engage the flat side walls 10^a of the recesses while 10 the extremities of the slats engage and slide upon the bottoms of the recesses. By constructing the parts in this manner and providing the inner ends of the notches or recesses 10 with walls 10^b, against which the 15 inner edges of the slats bear when the slats are collapsed, the dye liquor will be effectively prevented from passing around the ends of the slats. The ribs or projecting elements 11 are formed on the heads between 20 the recesses 10 for the purpose of supporting the end portions of the body of yarn on the beam when the slats are collapsed, thereby preventing the dye liquor from passing between the inner faces of the heads 5, 7 and 25 the adjacent or end portions of the body of yarn on the beam. I have found in practice that in order to do effective work with a collapsible dyeing beam, it is necessary to have a substantially fluid-tight engagement 30 between the heads of the beam and the ends of the slats and end portions of the body of yarn on the beam, when the slats are collapsed; and such connection between the parts is effected by the provision of the 35 inwardly-projecting lugs 11 and making the recesses 10 with closed inner ends 10^b the straight side portions 10^a.

The expanding mechanism for the slats 22 comprises in addition to the expanding rings 40 17, a series of cam shaped or beveled expanding blocks 26 attached to the inner edges of the slats, one of said blocks being disposed in each of the notches 21 in the expanding rings. The beveled edges of the expanding blocks are engaged with the inner ends of the notches 21 whereby, when the expanding rings are adjusted longitudinally in one direction on the shaft 1, the engagement of 45 said edges with the inner ends of the notches 21 will expand or force the slats 22 outwardly to a greater or less extent, and when said rings are shifted in the opposite direction the slats will be permitted to retract or collapse and thus relieve the pressure of the 55 slats on the yarn wound thereon.

The slat expanding rings are shifted to expand or permit the slats to retract by means of a ring adjusting or shifting screw 27 which is revolvably mounted in the head 60 7 of the beam and has its inner threaded end in operative engagement with a threaded aperture 28 in one of the spokes 19 on the adjacent end slat expanding ring. The screw 27 is swiveled or revolvably secured in 65 the head 7 and held against longitudinal

movement therein by a flange 29 arranged on the screw adjacent to the outer side of the head 7 and by a collar 30 fixed on the screw adjacent to the inner side of the head. The outer end of the screw 27 is squared as 70 at 31 to receive a wrench or handle, whereby the screw may be turned in one direction or the other. By arranging the screw 27 as herein shown and described, it will be readily seen that when the screw is turned in one direction the engagement of the threaded end thereof with the threaded passage 28 in the end expanding ring will draw said ring, together with the other rings connected therewith, toward the head 7 of the beam, 75 thus engaging the inner ends of the notches 21 in said rings with the beveled edges of the expanding blocks 26 of the slats to force the latter outwardly. It will also be seen that the reverse movement of the screw will shift the entire set of expanding rings in the opposite direction, thereby permitting the slats to retract or collapse.

In order to limit or regulate the movement of the expanding rings 17 and the consequent expansion or retraction of the slats 22, I provide a gage screw 32, the inner end of which is threaded and is engaged with a threaded aperture 33 in the spoke of the expanding ring opposite to the spoke having the threaded aperture 28. On the screw 32 adjacent to the outer side of the head 7 is arranged a stop flange 34 which is adapted to engage said outer side of the head and to thereby limit the inward or retracting movement of the expanding rings. On the screw 32 is an adjustable stop collar 35 which is adapted to be secured in its adjusted position on the screw 32 by a set screw 36. The collar 35 when adjustably secured to the screw 32 in the manner described will engage the inner side of the head 7 when the expanding rings are shifted outwardly or to operative positions for expanding the slats 22 and will thereby limit this movement of the expanding rings and the resulting projection or expansion of the slats.

In the head 7 of the beam within the central portion thereof surrounded by the flange 16 are a series of openings 37 through which the dyeing liquor is admitted to the beam from the tubular journal (not shown) but which is adapted in practice to be connected with the annular flange 16. By means of my improved adjusting mechanism it will be seen that the expanding rings may be readily adjusted to expand or to permit the yarn supporting slats to collapse, and that by providing the gage screw with its adjustable stop 35 as herein shown and described, the shifting movement of the rings can be readily regulated to cause the rings to expand the slats to the desired extent. By providing the slat engaging lugs 11 and 130

forming the ends of the slats to closely fit the recesses 10 in the heads of the beam; the dye liquor admitted through the openings 37 in the head 7 will be prevented from 5 channeling or working around or between the ends of the slats and the adjacent parts of the head thus causing the dye liquor to pass through the yarn wound on the slats.

The use and operation of the invention is 10 as follows: Assuming the beam is empty, the screw 27 is turned in the proper direction to expand the slats 22 and the gage screw or member 32 is then screwed inwardly to bring the flange 34 against the outer face 15 of the head 7 for the purpose of getting the outer end of said screw 32 out of the way and permitting the beam to be readily placed in the warper and also for the purpose of causing said screw 32 to assist the screw 27 20 in bracing the expanding rings 17. When the beam is thus expanded, it is placed in the warper and the yarn wound thereon in the usual manner, after which the beam is removed from the warper and the gage 25 screw 32 is run out until the stop collar 35 engages the inner face of the head 7. The shifting screw is then turned in the proper direction to cause the slats to collapse, this movement of the screw being continued until 30 the stop 34 of the gage screw 32 again engages the outer face of the head 7, whereupon the beam will be fully collapsed and it may be placed in the dye vat or machine. It will be observed that by constructing and 35 arranging the gage or stop device in this manner, it will be very easy for the operator to determine the position of the slats, even though they are covered with the yarn.

From the foregoing description, taken in 40 connection with the accompanying drawings, the construction and operation of the invention will be readily understood without requiring a more extended explanation.

Various changes in the form proportion, 45 and the minor details of construction may be resorted to without departing from the principle or sacrificing any of the advantages of this invention, as defined in the appended claims.

Having thus described my invention, what 50 I claim is;

1. In a revolving collapsible dyeing beam, 55 a supporting shaft, heads fixed thereon, a plurality of slat expanding rings slidably mounted on said shaft, a plurality of radially movable slats supported and expanded by said rings, means on said heads to receive the ends of the slats and to provide a substantially fluid tight engagement between 60 the heads and ends of the slats when the latter are collapsed, and means whereby said expanding rings are adjusted to expand the slats or to permit the latter to collapse.

2. In a revolving collapsible dyeing beam, 65 a supporting shaft, heads fixedly mounted

thereon and having in their inner sides a plurality of radially disposed slat receiving notches, a plurality of yarn supporting slats having their ends slidably and closely engaged with said recesses, a plurality of slat engaging lugs arranged on said heads between said recesses to provide a substantially fluid tight engagement with the slats, said lugs projecting inwardly beyond the inner faces of the heads and adapted to be engaged by the yarn on the beam when the slats are collapsed, whereby the dye liquor will be prevented from passing between the inner side faces of the heads and the end portions of the body of the yarn on the beam, said recesses being of greater length than the width of the slats, whereby, the latter are permitted to move freely between the lugs, a series of slat expanding rings slidably mounted on the shaft and having an operative engagement with said slats, and means whereby said rings are adjusted to expand the slats and to permit the latter to collapse.

3. In a revolving collapsible dyeing beam, 90 a supporting shaft, slat supporting heads fixed on said shaft, a plurality of yarn supporting slats having an adjustable, substantially fluid tight engagement with said heads, a plurality of slat expanding rings 95 slidably mounted on said shaft and having an operative engagement with said slats, whereby, the latter are expanded and permitted to retract, a ring adjusting screw swiveled in one of said heads and having its 100 threaded inner end engaged with the adjacent endmost expanding ring, whereby, said rings are adjusted to expand said slats and to permit the same to collapse, an adjustable gage adapted to limit the movement of said expanding rings thereby regulating the expansion of said slats, and means to connect said rings together, whereby, they are moved in unison.

4. In a revolving collapsible dyeing beam, 110 a supporting shaft, slat supporting heads fixed on said shaft, a plurality of yarn supporting slats having an adjustable, substantially fluid tight engagement with said heads, a plurality of slat expanding rings 115 slidably mounted on said shaft and having an operative engagement with said slats, whereby, the latter are expanded and permitted to retract, a ring adjusting screw swiveled in one of said heads and having its 120 threaded inner end engaged with the adjacent endmost expanding ring, whereby, said rings are adjusted to expand said slats and to permit the same to collapse, a gage screw having a threaded engagement with one of 125 said expanding rings and having a sliding engagement with the adjacent head of the beam, a stop flange on said screw to engage the outer side of said head, whereby, the movement of said expanding rings is limited 130

- in one direction and a stop collar adjustably secured to the screw adjacent to the opposite side of said head, whereby, the adjustment of the expanding rings in the opposite direction is controlled or regulated.
5. In a hollow revolving collapsible dyeing beam, the combination with a series of spaced apart, collapsible slats and means for shifting the same, of fixedly connected beam heads provided with guideways for the ends of the slats, and elements extending inwardly from the inner faces of the heads and adapted to be engaged by the yarn on the beam when the slats are collapsed, whereby
- 10 15 the dye liquor is prevented from passing between the inner faces of the heads and the end portions of the body of yarn on the beam.
6. In a hollow revolving collapsible dyeing beam, the combination of a shaft, heads thereon and formed in their inner faces with recesses having unbroken side walls united with an inner end wall, a series of collapsible slats having their ends slidably engaging
- 20 25 both side walls of said recesses, the inner edges of said slats being adapted to engage the inner end walls of the recesses when the slats are collapsed to provide a fluid-tight

engagement of the ends of the slats with the heads, and means for actuating said slats.

30

7. In a hollow revolving collapsible dyeing beam, the combination of a shaft, heads thereon and formed with slat-receiving recesses having side walls uniting with inner end walls, a series of longitudinal rods arranged at a distance from the shaft and connecting the heads, a series of collapsible slats having ends slidably engaged with the recesses in the heads, inwardly-projecting lugs on the inner faces of the heads and disposed between said recesses, said lugs being adapted to support the end portions of the body of yarn on the beam when the slats are collapsed, series of cams on said slats, series of rigidly connected rings slidably arranged on the shaft and having notches to receive

35

40

45

45 said cams, and an operating screw swiveled in one of said heads and having a threaded engagement with one of the endmost rings.

In testimony whereof I have hereunto set 50 my hand in presence of two subscribing witnesses.

FRANK M. MORTON.
